SIZING AND FINISHING MACHINE

William G. Maloney and Neil E. Boyer, Mexico,
Mo., assignors to A. P. Green Fire Brick Com-
pany, Mexico, Mo., a corporation of Missouri

Application March 17, 1941, Serial No. 383,696

13 Claims. (Cl. 25—104)

Our invention relates to sizing and finishing machines and, more particularly, to machines for sizing and finishing clay brick or tile.

In manufacturing a brick or tile by means of the well known "stiff mud" process in which process an endless column of clay is extruded through a die, the individual bricks or tile are formed by cutting transversely across this clay column at intervals with suitable wires, such as piano wires. These cut clay brick or tile are known to the trade as "wire cut brick." While the column of clay extruded from the die is generally smooth and even, the ends of the brick or tile which are cut from the clay column by the wires are ragged and uneven. After the bricks are cut, they are run through presses to square the blanks. The pressing operation, of course, generally smooths the ragged ends where the column has been cut by the wires.

However, in certain types of "wire cut" brick or tile which cannot be easily pressed, the ends are now left rough and uneven or they are somewhat smoothed by a hand trowel. Obviously, this hand method of smoothing the ends is time consuming, costly and generally unsatisfactory.

Our invention has for its principal object a machine for smoothing and sizing clay brick or tile or other objects and especially "wire cut" bricks which cannot be easily pressed; which will quickly, efficiently and effectively size and smooth a brick or tile blank. A further object is to devise a machine which is of simple yet durable construction and which may be easily and quickly adjusted for brick or objects of varying sizes.

The invention consists principally in providing a sizing and finishing machine having two adjustable spaced rotary disks and a movable carriage whereon a brick or tile blank may be placed, providing guides for moving the carriage with the brick thereon between the rotating disks whereby the end of the brick or object is smoothed and finished. Our invention further consists in the parts and combinations and arrangements of parts hereinafter described and claimed.

In the accompanying drawings wherein like reference numerals refer to like parts wherever they occur,

Fig. 1 is an end view of a sizing and finishing machine embodying our invention,

Fig. 2 is a side view of the machine,

Fig. 3 is a top plan view of the machine; and

Fig. 4 is a sectional view taken on the line 4—4 of Fig. 3.

Our machine for sizing and finishing "wire cut" brick or tile comprises a suitable supporting

framework that includes a table 1 having legs 2 at the corners thereof and a shelf or lower table 3 secured to the legs.

Mounted on the table 1 and extending transversely across the middle portion thereof are channel-shaped guides 4 which are positioned sideways and are supported above the table by legs 5 secured to the ends of the guides. Mounted in the guides and adapted to move therewith are 5 a movable carriage or table 6 having rollers 7 secured to the sides thereof, said rollers 7 being placed in the channel-shaped guides 4 and rolling therein. Resting on the carriage and secured thereto by screws 1a is a pallet or tray 8 preferably made of wood or other suitable material for holding a brick or tile 8a to be sized or finished. An end wall 9 secured to the outer end of the tray 8 is provided as a rest for the tile or brick. Said carriage is provided with a suitable handle 10 for manually moving the carriage and tray carried thereby transversely across the middle portion of the table in the guides 4. However, any suitable automatic means for moving the carriage and tray resting thereon may be provided.

20 Mounted on the ends of said table 1 and secured thereto are opposed stationary brackets or pedestals 11 connected at their lower ends by two guide rods 12 which extend longitudinally across the table. The ends 13 of these guide rods are threaded and extend through openings in the base portion of the pedestals. The ends of these guide rods have nuts 14 screwed on the threaded ends thereof. Movably mounted on said guide rods 12 which extend through openings in the lower portions thereof are movable brackets or followers 15. Suitable guide rod bushings 16 are provided for these openings in said followers 15.

Opposed rotatable disks 17 fixed on drive shafts 18 are provided, each drive shaft being journaled 25 in suitable bearings in one of the pedestals 11 and the adjacent follower 15. These drive shafts extend outwardly from said pedestals 11 and are so mounted that they may slide endwise in respect to said pedestals. Mounted on the ends of the drive shafts and having their hubs abutting against the pedestals are pulleys 19, preferably having a V-shaped groove 20. The shafts have longitudinal grooves 21 therein and the pulleys have internal grooves therein for receiving keys 22 adapted to make said pulleys rigid with said shafts. These keys are mounted rigid with the pulley but are slidable in the shaft grooves 21. Said keys 22 extend through said pedestals 11 and terminate in projecting lugs 23 which abut 30 against the inner faces of said pedestals to pre-

55

vent the pulleys from moving endwise in respect to the pedestals. Any other suitable spline arrangement may be used if desirable.

Extending longitudinally across the table between the guide rods 12 and passing through openings in the followers 15 is an adjusting rod 24. The ends of this rod are rotatably mounted in the pedestals 11. One end 25 is threaded and extends through an adjusting wheel 26 fixed on said adjusting rod. A lock nut 27 is screwed on the threaded end 25 and is adapted to clamp the wheel 26 between said nut 27 and the adjacent pedestal to prevent said adjusting rod from being rotated. The adjusting rod has two threaded portions 28, each being adjacent to the followers 15 and each being threaded in an opposite direction to the other. Mounted on each threaded portion 28 and pressed into the openings in the followers are internally threaded feed nuts 29, each being threaded in an opposite direction to the other. When the adjusting rod 24 is rotated by the wheel 26, the followers are forced inwardly or outwardly on the guide rods 12 depending on whether the adjusting rod is rotated clockwise or counter-clockwise.

Belts 30 are mounted in the pulley grooves 20 and adapted to drive the disk shafts 18 and mounted in pulleys 31 fixed on the counter-shaft 32. This counter-shaft is journaled in pedestals 33 secured to the shelf 3. A three-step pulley 34 is fixed on the counter-shaft 32 and is connected with a pulley 36 rigid with the main shaft 37 of a motor 38 by a belt 35. This motor may be of any type but is preferably an electric motor.

In the operation of the hereinbefore described device, the distance between the rotating disks 17 is adjusted by means of the wheel 26 rotating the adjusting rod 24. The motor 38 rotates the rotary disks and the sizing and finishing machine is ready to size and finish a brick, tile or other object. A brick, tile or other object, is placed on the pallet 8 at the edge of the table and the carriage 6 with the pallet mounted thereon is pushed between the rotating disks. The disks are set so that they are spaced about the proper length of a brick or other object. When the brick passes between the disks, the excess material is cut off and the ends are smoothed by the rotation of the disks.

Obviously, objects other than bricks may be sized and finished in our machine and also numerous modifications of the machine may be made. Consequently, we do not wish to be limited to the precise construction shown.

What we claim is:

1. A sizing and finishing machine for articles of unfired clay and the like comprising spaced rotatable disks each having a cutting edge and a smoothing face and a carriage movable between said disks.

2. A sizing and finishing machine for articles of unfired clay and the like comprising opposed spaced rotatable disks each having a cutting edge and a smoothing face, a movable carriage, guides for said carriage extending between said disks, and means for rotating said disks.

3. A sizing and finishing machine for articles of unfired clay and the like comprising spaced rotatable disks each having a cutting edge and a smoothing face, means for adjusting the space between said disks, a carriage movable between said disks, and means for rotating said disks.

4. A sizing and finishing machine for articles of unfired clay and the like comprising opposed spaced rotatable disks each having a cutting edge

and a smoothing face, means for adjusting the space between said disks, a movable carriage, guides for said carriage extending between said disks, and means for rotating said disks.

5. A sizing and finishing machine for articles of unfired clay and the like comprising spaced rotatable disks each having a cutting edge and a smoothing face and having drive shafts, a movable support and a stationary support for each of said shafts, said shafts being journaled in said supports, means for rotating said drive shafts and a carriage movable between said disks.

6. A sizing and finishing machine for articles of unfired clay and the like comprising spaced rotatable disks each having a cutting edge and a smoothing face and having drive shafts, a movable support and a stationary support for each of said shafts, said shafts being journaled in said supports, means for moving said movable supports thereby adjusting the space between said disks, means for rotating said drive shafts and a carriage movable between said disks.

7. A sizing and finishing machine for articles of unfired clay and the like comprising opposed spaced rotatable disks each having a cutting edge and a smoothing face and having drive shafts, a movable support and a stationary support for each of said shafts, said shafts being journaled in said supports, means for moving said movable supports thereby adjusting the space between said disks, means for rotating said drive shafts and a carriage movable between said disks, said carriage being movably mounted in guides extending between said disks and transversely of said drive shafts.

8. A brick blank sizing and finishing machine comprising spaced parallel rotatable disks, each of said disks having a cutting edge and a smoothing face and a drive shaft, said drive shafts being axially aligned, a movable support and a stationary support for each of said drive shafts, said shafts being journaled in said supports, guides for said movable supports, means for moving said movable supports thereby adjusting the space between said disks, means for rotating said drive shafts, and a carriage movable between said rotatable disks.

9. A brick blank sizing and finishing machine comprising opposed spaced rotatable disks, each of said disks having a cutting edge and a smoothing face and a drive shaft, a movable support and a stationary support for each of said drive shafts, said shafts being journaled in said supports, guides for said movable supports, means for moving said movable supports thereby adjusting the space between said disks, means for rotating said drive shafts, a carriage movable between said rotatable disks, said carriage being movable in guides extending between said disks and transversely of said drive shafts.

10. A brick blank sizing and finishing machine comprising opposed spaced rotatable disks, each of said disks having a cutting edge and a smoothing face and a drive shaft, a movable support and a stationary support for each of said drive shafts, said shafts being journaled in said supports, guides for said movable supports, an adjusting rod for moving said movable members and thereby adjusting the space between said disks, means for rotating said drive shafts, a carriage movable between said rotatable disks, said carriage movable in guides extending between said disks and transversely of said drive shafts.

11. A brick sizing and finishing machine comprising a table, parallel opposed spaced rotatable

cutting and smoothing disks movable longitudinally of said table, each of said disks having a drive shaft mounted in a pedestal member secured to said table and in an inner movable member, said drive shafts being axially aligned, guide rods connecting said stationary pedestal members, said movable members being movably mounted on said guide rods, an adjusting rod extending parallel to said guide rods, said adjusting rod extending through oppositely threaded openings provided therefor in said movable members, said adjusting rod having oppositely threaded portions adjacent to said movable members whereby said movable members may be moved longitudinally when said adjusting rod is rotated to change the space between said disks, means for rotating said adjusting rod, laterally open channel-shaped guides extending transversely across said table between said disks, a movable carriage having rollers mounted in said guides and movable therein, said carriage adapted to move between said disks, and means for rotating said drive shafts.

12. A brick sizing and finishing machine comprising a table, parallel opposed spaced rotatable cutting and smoothing disks movable longitudinally of said table, each of said disks having a drive shaft mounted in a pedestal member secured to said table and in an inner movable member, said drive shafts being axially aligned, guide rods connecting said pedestal members, said movable members being movably mounted on said guide rods, an adjusting rod extending parallel to said guide rods and extending through oppositely threaded openings in said movable members, said adjusting rod having oppositely threaded portions adjacent to said threaded portions in

said movable members whereby said movable members may be moved longitudinally when said adjusting rod is rotated and the space between said disks changed, means for rotating said adjusting rod, laterally open channel-shaped guides extending transversely across said table between said disks, a movable carriage having rollers mounted in said guides and movable therein, said carriage adapted to move between said disks, and means for rotating said drive shafts.

13. A brick sizing and finishing machine comprising a table, opposed spaced rotatable cutting and smoothing disks movable longitudinally of said table, each of said disks having a drive shaft mounted in a stationary pedestal member secured to the end of said table and in an inner movable member, guide rods connecting said pedestal members, said movable members being movably mounted on said guide rods, an adjusting rod extending parallel to said guide rods and extending through openings in said movable members, oppositely threaded feed nuts in said openings, said adjusting rods having oppositely threaded portions adjacent to said movable members whereby said movable members may be moved longitudinally when said adjusting rod is rotated to alter the space between said disks, means for rotating said adjusting rod, laterally open channel-shaped guides extending transversely across the central portion of said table between said disks, a movable carriage having rollers mounted in said guides and movable therein, said carriage adapted to move between said disks, and means for rotating said drive shafts.
